UNITED STATES PATENT OFFICE.

THOMAS C. WELCH, OF CHICAGO, ILLINOIS; JAMES M. LYNN, ADMINISTRATOR OF
SAID WELCH, DECEASED.

BOOK-STITCHING MACHINE.

Application filed August 4, 1923. Serial No. 655,554.

My invention relates to a book stitching machine and has particular reference to a machine for stitching together the signatures making up a book after they have been arranged in order by the gathering machine and in addition to sewing the signatures together preliminary to having the covers applied thereto, performs the function of attaching reinforcing or binding strips along the rear edges of the book so that the covers are more securely attached to the book and also are very much stronger and more durable in service.

Another and further object of my invention is the provision of a machine for stitching books of unusual thickness by providing as a part of my machine means for forming spaced holes through the rear edges of the book and thereafter running the book underneath a sewing machine so that the needle from the sewing machine passes through the holes formed in the book and thus avoids the necessity of forcing the sewing machine needle through the book, which has not been possible to accomplish heretofore except in books which are comparatively thin.

Another and further object of my invention is the provision of a machine which accomplishes in a single unit structure a plurality of operations which have heretofore been performed independently of each other and I am therefore able to effect a material saving in labor cost and also provide a more effective method of performing what has heretofore been a laborious and expensive operation in the book binding art.

These and other objects of my invention will be more fully and better understood by reference to the accompanying sheets of drawings, and wherein—

Figure 1 is an elevational view of the front side of my improved machine;

Figure 2 is an elevational view of the rear side of the machine;

Figure 3 is a plan view of the machine shown in Figures 1 and 2;

Figure 4 is a detail view partially in elevation and partially in section along line 4—4 of Figure 3;

Figure 5 is a detail view partially in elevation and partially in section on line 5—5 of Figure 3;

Figure 6 is a vertical cross-sectional view on line 6—6 of Figure 3;

Figure 7 is a detail sectional view on line 7—7 of Figure 6;

Figure 8 is a cross-sectional view through the machine on line 8—8 of Figure 1; and

Figure 9 is a vertical detail sectional view on line 9—9 of Figure 1.

Referring now specifically to the drawings, and in which like reference characters refer to like parts throughout, a machine frame 10 is shown having a work table 11 mounted thereon in any approved manner, as by a plurality of upwardly extending arms 12, 12. Mounted upon the lower part of the machine is a motor 13, through which power is supplied for the operation of the feeding and stitching apparatus, as will be more fully described hereinafter. Mounted on the front end of the frame 10 of the machine in movable blocks 14, 14, upon a shaft 14^a is a pulley 15, the blocks 14, 14 being mounted in brackets 16, 16, which have downwardly projecting adjusting screws 17, 17, at the upper sides thereof and with upwardly projecting adjusting screws 18, 18, at the lower sides thereof, the blocks 14, 14 being positioned between the points of the screws 17 and 18 to provide for vertical adjustment of the shaft 14^a. At the opposite end of the machine, mounted upon a transversely extending shaft 19 in a pair of brackets 20 and 21 is a similar pulley 22, the shaft 19 upon which the pulley is mounted being secured in a plurality of vertically movable blocks 23, 23, with downwardly extending upper adjusting screws 24, 24, located in the tops of the brackets and upwardly projecting lower screws 25, 25 being positioned in the lower side of the brackets 20 and 21 by means of which a vertical adjustment of the pulley 22 is accomplished, the said pulleys 15 and 22 being in alignment with each other and having an upper endless steel feed belt 26 extending thereover. Mounted upon a shaft 27 secured in bearing blocks 28 secured to the frame 10 of the machine is a pulley 29, the position of this pulley being fixed with relation to vertical movement and being in alignment with another pulley 30 near the rear end of the machine, which is mounted upon a transversely extending shaft 31 secured to

the machine frame 10 in any approved manner and which has a gear wheel 32 attached to the outer end thereof through which power is supplied by means of a chain of 5 gears to the pulley 22, as will be more fully described hereinafter. The said pulleys 29 and 30 are in alignment with each other and are also in alignment with the pulleys 15 and 22 but are smaller in diameter than 10 the said pulleys 15 and 22 and have a steel feed belt 33 extending thereon, the upper portion of which runs underneath the belt 26 and passes over a plurality of rollers 34, 34, which are mounted in a channel 35 15 formed in the table 11. Secured to the table 11 is a plurality of pivotally mounted arms 36, 36, by means of brackets 37, 37 through which a longitudinally positioned shaft 38 extends, the said arms 36 having adjusting 20 screws 39, 39 on the outer ends thereof and in threaded engagement therewith by means of which the arms 36 can be adjusted by the operator, the lower ends of the screws 39 contacting with the table 11. Mounted 25 upon the forward ends of the arms 36 is a plurality of yokes 40, 40, which carry a frame 41 having a plurality of rollers 42, 42, mounted therein and underneath which the feed belt 26 passes, and by means of 30 which a predetermined pressure is maintained upon the book 42^a as it passes underneath the drills and sewing apparatus.

Mounted upon the front side of the machine frame 10 is a pair of vertically extending arms 43 and 44 having a horizontally extending rod 45 in the upper ends thereof with a similar parallel extending rod 46 mounted in the said members 43 and 44, with pair of adjustably mounted vertically 40 extending rods 47 and 48 extending between the rods 45 and 46 and upon which is slidably mounted a drill head 49 having a plurality of drill chucks 50, 50 mounted therein, with drill bits 51, 51 positioned 45 therein and having a guide 52 at the bottom thereof with guiding plugs 52^a therein, the guide member being carried by a pair of rods 52^b, 52^b, with springs 53 mounted upon the rods 52^b, 52^b for assisting the drill bits 50 in clearing themselves from the book during the operation of the machine. The guide 52 is positioned against an angle member 54 secured to a channel member 55, which in turn is secured to the bed 11 in 55 any approved manner, the member 55 having a channel 56 therein within which are positioned a plurality of rollers 57, 57 to support the book 42^a during the drilling operation and between which the points of 60 the drill bits 51 extend during the drilling operation after they pass through the book 42^a. The drill bits are spaced apart from each other a suitable distance with the drill bits placed in set relation with each other, 65 that is, the front drill is set farthest down,

so that a hole will not be drilled completely through the book with the first operation, but will only be partially drilled and thereafter as the book is moved forward each succeeding drill bit completes the drilling 70 operation until a plurality of holes are drilled in the book 42^a as it is passed underneath the drill.

Mounted in the drill block 49 upon the upper end of the chucks 50 is a plurality of 75 gears 58, 58 which are in mesh with each other and through which motion is communicated to all of the drill chucks mounted in the drill head 49 with a central shaft 59 being provided having a beveled gear 60 at 80 its upper end which is in mesh with a second beveled gear 61 mounted upon a shaft 62 which is connected to an electric motor 63 by a universal coupling 64, so that during the 85 operation of the machine the drill bits are constantly operated by the motor 63, the said motor being mounted upon a supporting member 63^a secured to the table 11. An arm 65 is provided which is connected to the 90 drill head 49 by a bolt 66 and which in turn is connected to an eccentric sleeve 67 mounted upon an eccentric 68, which, in turn, is mounted upon a shaft 69, the said shaft 69 being secured to the frame 10 in any suitable 95 manner and has a sprocket wheel 70 secured thereto over which a sprocket chain 71 operates leading to the power mechanism, which will be described in detail 100 hereinafter, and by means of which the entire drill head 49 is moved up and down in synchronism with the feeding movement of the book 42^a through the machine by the feed bits and operating means therefor which will also be more fully described hereinafter.

Mounted upon the feed table 11 of the machine is a sewing head 72, this sewing head being of the heavy commercial form of sewing heads usually supplied for this purpose and comprises a shaft 73 having a fly wheel 74 mounted thereon and operated by a train of gear wheels 75, 76, 77 and 78, which derive their source of power from the motor 13 by suitable gear connections. At the outer end of the sewing head 72 is mounted a reciprocating needle holding member 79 having a sewing needle 80 mounted therein, the holding member 79 being mounted upon an arm 81 in the usual 110 fashion of sewing machines of this character, with a thread holder 82 being provided through which a thread 83 is supplied which passes through a tension 84 and downward in the needle 80 in the usual manner of machines of this character. The thread 83 is taken from a spool 80^a mounted upon a spindle 80^b secured in a holding block 80^c and passes through a thread guide 80^d and thence to the holder 82. Underneath the 115 table 11 is mounted a bobbin 85 in a 120

tatable bobbin holding device 86 in the usual manner and from which an underneath thread 87 is supplied during the stitching operation of the books, it being understood that the needle passes through the holes made in the books 42^a heretofore described, and are sewed by means of a lock stitch in exactly the same manner that ordinary sewing is effected by sewing machines. The 10 bobbin carrier 86 is operated by means of a member 88 mounted upon a shaft 89, with an eccentric portion 88^a which is in engagement with a roller 90 mounted upon a pivotal arm 91, to the outer end of which is connected an upwardly extending member 92 to the upper end of which a presser foot 93 is connected, a tubular member 94 being provided within which a spring 95 is positioned, which normally holds the presser foot up 15 out of engagement with the book 42^a and into engagement with the eccentric member 88^a, the arm 91 at its opposite end being secured to a downwardly extending member 96 secured to the underneath side of the 20 bed 11, the presser foot operating in synchronism with the sewing needle 80.

The motor 13 has a belt 97 extending upward therefrom and over a pulley 98 mounted upon a transversely extending shaft 99 with a clutch mechanism 100 mounted upon the shaft 99 and having an operating fork 101 operated by an arm 102 connected thereto with a longitudinally extending rod 102^a extending to the front end of the machine 35 where an operating rod 103 leading to a foot pedal 103^a places the clutch 100 under the control of the operator and by means of which the machine is thrown into and out of operation.

40 Mounted on the shaft 99 is a gear pinion 104 which is in mesh with a second pinion 105 which is mounted upon the shaft 89 which extends transversely across the frame 10 of the machine from side to side and on 45 the outer end of which, on the rear side of the machine is mounted the pinion 78, one of the train of gears through which power is communicated to the sewing apparatus heretofore described. On the outer side of 50 the gear pinion 78 is a thimble 106 positioned in the gear pinion 78 at one side of the center thereof and which is adapted to engage in recesses 107 in the outer periphery of a star gear wheel 108 mounted upon a 55 shaft 108^a secured to the frame 10. Between each of the recesses 107 on the gear 108 is formed a plurality of teeth 109 having a curved recess 110 in the ends thereof and into which a hub portion 111 of the gear 60 wheel 78 is adapted to seat, the engagement of the hub 111 into the recess 110 holding the wheel 108 stationary for a short fraction of time during a partial rotation of the thimble 106 which, because of its engagement in the recess 107 moves the wheel

108 intermittently in a step by step motion and thus imparts to the feeding mechanism an intermittent movement of these parts, thereby feeding the books into the machine and holding them stationary while one 70 movement of the drill head 49 is made and also a movement of the sewing needle 80. The shaft 31 extends across the frame 10 of the machine and has a gear 112 mounted thereon at the rear side of the machine 75 which meshes with a second gear 113 mounted upon the shaft 108^a and through which movement is communicated by means of the shaft 31 to the pulley 30 mounted thereon and which controls the movement of the 80 inner feed belt 33. The shaft 31 has a gear wheel 114 mounted on the outer end thereof on the front side of the machine which in turn connects by means of a train of gears 115, 116, 117 and 118, which last 85 mentioned gear is mounted upon the shaft 19 carrying the pulley 22 which carries the outer feed belt 26, these gear connections serving to move the two feed belts simultaneously and in synchronism with the other 90 operating parts of the machine, and in an intermittent step by step movement.

Attached to the outer end of the shaft 89 is a fly wheel 119 which serves to steady the motion of the machine, the said shaft 89 95 also having a gear wheel 120 mounted thereon at the front side of the machine and which meshes with a second gear wheel 121 carrying a smaller spur gear 122 which is in mesh on one side with a gear wheel 123 having an eccentrically shaped channel 124 in its outer face within which a roller 125 mounted on the end of a bell crank 126 travels, the bell crank lever being pivotally mounted on a stud 127 secured to the frame 10 of the machine and having a rod 128 connected thereto by means of a pin 129, the said rod 128 being connected to a pivotally mounted lever 130 at the front of the machine by means of a pin 30^a, the said lever 105 110 having a slot 131 at its upper end through which a pin 132 extends into a sliding block 133 which is mounted upon a guide member 134 secured to the frame 10 of the machine in any approved manner. The 115 block 133 has a face plate 135 secured thereto and also has an arm 136 attached thereto which has a parallel extending screw 137 at its upper end with adjusting nuts 138 and 139 mounted thereon, the screw 137 having a 120 plate 140 attached thereto to which a feeding member 141 is attached and which extends underneath the upper belt 26 and rides upon the top of the feed table 11 and serves to push the books 42^a forward until the books are gripped between the upper feed belt 26 and the upper portion of the inner feed belt 33, the books being hand fed in the front of the block 141 and underneath the belt 26 by being pushed along the top 125 130

of the table 11 until they are in contact with the guide member 54 which extends at the outer side of the table 11. A similar guide member 142 is provided at the inner side of 5 the book which serves to hold the books in from pushing out sidewise between the feed belts during the drill and sewing operations. It will thus be understood that as the machine operates, the bell crank 126 reciprocates the rod 130 which in turn moves the block 133 and the feeding block 141 back and forth underneath the belt and pushes the books forward to a point where they are gripped by the feeding belts and carried 15 through the machine.

Mounted upon the lower side of the frame 10 upon a pair of arms 143 is a reel 144 carrying a roll 145 of reinforcing material, such as muslin, heavy manilla paper or the 20 like, and which is fed over a gum applying roller 146 mounted upon the upper side of a receptacle 147 which is secured to the frame of the machine and from which a strip of material 148 is run underneath a roller 149 25 around a second roller 150 to a point immediately above the belt 33 where the strip 148 is fed on top of the belt 33 with the gum side upward in position to be applied to the books 42^a as they are fed in between 30 the lower belt 33 and the upper belt 26. A similar reel 151 from which a strip of material 152 leads is provided which passes over a gum applying roller 153 mounted in a receptacle 154 at the upper side of the 35 machine with retaining rolls 155 and 156 being provided to hold the strip 152 in contact with the surface of the roller 153 so that mucilage or paste is applied to the undersurface of the strip 152. The strip 152 passes 40 longitudinally of the machine around a pulley 157 carried by a standard 158 mounted upon the outer end of the rod 45 and thence back around another roller 159 mounted upon a standard 160, thence down- 45 ward around another roller 161 where the strip is fed underneath the said roller 161 and on to the rear edges of the books 42^a after they have left the drill press and before they reach the sewing machine, where 50 both reinforcing strips are sewed to the books 42^a as they pass through the machine. It will thus be understood that reinforcing strips are applied to the books as they pass through the machine upon each side thereof 55 and are fixed in position by the same stitching operation which sews the signature sheets together.

In mesh with the gear wheel 122 at the front side of the machine is a gear wheel 60 162 on the outer side of which is a cam 163 having a recess 164 in its outer face thereof with an arm 165 being provided intermediate the ends of which is a roller 166 which travels upon the surface of the cam 65 163. An arm 167 is provided to which the

arm 165 is pivoted with a slidably mounted member 168 at the upper end of the lever 165 and which slides in a U-shaped guide 169, the said member 168 having a rod 170 at the inner end thereof, to which a spring 70 171 is attached, the said spring being anchored at its opposite end to the frame 10 of the machine by means of a bolt 172 and exerting an inward pull upon the member 168 and holding the roller 166 in contact with the cam member 163. An up-standing member 173 is provided upon which is mounted a gear wheel 174 by means of a spindle 175 and which is in engagement with a toothed rack 176 fixedly mounted on 80 the upper side of the member 169. The member 173 has a rotary cutting member 177 mounted on its upper end with a gear wheel 178 at one side thereof and in engagement with the gear 174, this member 85 traveling inward and serving to cut the threads which continue from one book to another after they are stitched, the rotary cutter passing between the books 42^a as they travel between steel feed belts and thus serve 90 to separate these books after they are stitched by the sewing apparatus. This cutting wheel 177 also cuts the reinforcing strips 148 and 152 so that the books are separated from 95 each other as they are fed forward by the belts and discharged from the machine. At the rear of the machine is a U-shaped member 179 having a shaft 180 located therein upon the inner end of which is mounted a roller 181 and upon which the books are 100 discharged as they leave the lower feed belt 33 and on to a discharge chute 182 which passes downward transversely across the machine and delivers the books to the back side thereof where they are picked up by an 105 operator and placed upon a truck or a conveyor, as may be desired.

In operation the machine is entirely automatic and it will be understood that the operator, as heretofore described, places the 110 blank books upon the table 11 at the front end of the machine, and pushes them underneath the upper feed belt 26 and in front of the block 141 where they are pushed forward, where the books are gripped tightly between the rollers mounted in the frame 46 and the lower rollers 34 mounted in the channel 35 in the bed 11 and are conveyed by the feed belts in an intermittent step by 115 step motion underneath the drill bits where holes are formed in the rear marginal edges of the books 42^a, the lower binding strip 148 having been applied to the blanks in the meantime and they are then conveyed underneath the sewing head so the holes are in 120 register with the sewing apparatus, the upper binding strip in the meantime having been applied thereto and are conveyed past the reciprocating cutter belt where the binding strips and the thread are cut and the 125 130

books conveyed to the rear of the machine, where they are discharged onto the roller 181 and into the discharge chute 182 and delivered at the side of the machine.

5 While I have described more or less precisely the details of construction, I do not wish to be understood as limiting myself thereto, as I contemplate changes in form and the proportion of parts and the substitution of equivalents as circumstances may suggest or render expedient without departing from the spirit or scope of my invention.

I claim:—

1. A book stitching machine, comprising in combination a frame, a sewing head mounted upon said frame, a conveyor adapted to transport the books underneath the sewing head, and an automatic feeding device adapted to move the book onto the 20 automatic conveyor.

2. A book stitching machine, comprising in combination, a frame, a sewing head carried by said frame, a pair of conveyor belts mounted upon said frame, one of said belts 25 being positioned above the other, means for feeding a book between said conveyor belts, and gear operating mechanism adapted to intermittently actuate said conveying belts.

3. A book stitching machine, comprising in combination, a frame, a work table mounted upon said frame, a sewing head, a pair of endless conveyor belts mounted one 35 inside the other, a plurality of pivotally mounted arms, a frame carried by said arms, rollers mounted in said frame adapted to contact with the upper belt, and means carried by said arms whereby the upper feed belt is moved toward or away from the said lower belt.

40 4. A book stitching machine, comprising in combination, a frame, a work table carried by said frame, a sewing head mounted upon said frame, a plurality of endless conveyor belts in alignment with each other and adapted to carry a book between said belts, means to form holes in the book before it 45 passes under the sewing head, and means whereby the conveyor belts are caused to travel intermittently.

5. A book stitching machine, comprising in combination, a frame, a work table carried by said frame, a sewing head mounted upon said frame, a plurality of endless conveyor belts in alignment with each other 55 and adapted to carry a book between said belts, means to form holes in the book before it passes under the sewing head, and means whereby the conveyor belts are caused to travel intermittently and position the 60 holes under the sewing needle.

6. A book stitching machine, comprising in combination, a frame, a work table carried by said frame, a sewing head also mounted on said frame, a plurality of endless conveyor belts adapted to carry a book, and a

reciprocating head adapted to form holes in said book before it passes under the sewing head, and means whereby the said conveyor belts are caused to travel intermittently.

7. A book stitching machine, comprising in combination, a frame, a work table carried by said frame, a sewing head also mounted upon said frame, a plurality of endless conveyor belts adapted to carry a book, a reciprocating drill head carrying a plurality of drill bits adapted to form holes in said book before it passes under the sewing head, an eccentric gear connection to said drill head for moving the same, and means whereby the conveyor belts are actuated intermittently, the said drill head being actuated in synchronism with the travel of the said feed belts.

8. A book stitching machine, comprising in combination, a frame, a work table carried by said frame, a sewing head also mounted upon said frame, a plurality of endless conveyor belts adapted to carry a book, a reciprocating drill head carrying a plurality of drill bits adapted to form holes in said book before it passes under the sewing head, an eccentric gear connection to said drill head for moving the same, and means whereby the conveyor belts are actuated intermittently, the said drill head being actuated in synchronism with the travel of the said feed belts in stepped relation with each other.

9. A book stitching machine, comprising in combination, a frame, a feed table mounted thereon, a pair of endless conveyor belts mounted upon said frame, an automatic feeding device adapted to move the books between said conveyor belts, a drill head carrying a plurality of drill bits, means for causing the said conveyor belts to travel intermittently, and means whereby the said drill head is actuated in synchronism with the travel of the said feed belts.

10. A book stitching machine, comprising in combination, a frame, a work table mounted upon said frame, a pair of endless conveyor belts mounted upon said frame, said belts being in vertical alignment with each other, a sewing head mounted upon said frame, means for attaching reinforcing strips to the outer sides of the said book as it passes through the said machine and before it passes under the sewing head.

11. A book stitching machine, comprising in combination, a frame, a work table mounted upon said frame, a pair of endless conveyor belts mounted upon said frame, said belts being in vertical alignment with each other, a sewing head mounted upon said frame, means for attaching reinforcing strips to the outer sides of the said book as it passes through the said machine and before it passes under the sewing head, and means for applying an adhesive to the said

reinforcing strips before they are applied to the said book.

12. A book stitching machine, comprising in combination, a frame, a work table mounted upon said frame, a pair of endless conveyor belts in vertical alignment with each other, a sewing head mounted upon the frame, an upper and lower roller carrying reinforcing strips, adhesive applying rollers over which said strips pass, and means for feeding the reinforcing strips to the said book as it passes through the said machine.

13. A book stitching machine, comprising in combination, a frame, a work table mounted upon said frame, a pair of endless conveyor belts mounted upon said frame, said belts being in vertical alignment with each other, a drill mechanism adapted to form holes in said book, a sewing head mounted upon said frame, means for attaching reinforcing strips to the outer sides of the said book as it passes through the said machine and before it passes under the sewing head, and means for applying an adhesive to the said reinforcing strips before they are applied to the said book.

14. A book stitching machine, comprising in combination, a frame, a work table mounted thereon, a pair of conveyor belts in vertical alignment with each other, supporting means for said lower belt mounted in said work table, supporting rollers for said upper belt intermediate its ends, means adapted to force a book between said conveyor belts, a drill mechanism, a sewing head, a gear mechanism adapted to reciprocate the said drill mechanism and the said conveyor belt in synchronism with each other.

15. A book stitching machine, comprising in combination, a frame, a work table mounted thereon, a pair of conveyor belts in vertical alignment with each other, means to hold the said conveyor belts in spaced re-

lation with each other, a drill mechanism, a sewing head, a Geneva gear mechanism adapted to impart intermittent motion to said conveyor belts and an eccentric driving connection for reciprocating the said drill head.

16. A book stitching machine, comprising in combination, a frame, a work table mounted thereon, a pair of conveyor belts in vertical alignment with each other, means to hold the said conveyor belts in spaced relation with each other, a drill mechanism, a sewing head, a Geneva gear mechanism adapted to impart intermittent motion to said conveyor belts in an eccentric driving connection for reciprocating the said drill head, the said drill head having a resiliently mounted presser foot.

17. A book stitching machine, comprising in combination, a frame, a work table mounted thereon, a pair of conveyor belts in vertical alignment with each other, means to hold the said conveyor belts in spaced relation with each other, a drill head, a sewing head, a Geneva gear mechanism adapted to impart intermittent motion to said conveyor belts, an eccentric driving connection for reciprocating the said drill head, a drill guide yieldingly secured to said drill head.

18. A book stitching machine, comprising in combination, a frame, a work table mounted thereon, a pair of conveyor belts in vertical alignment with each other, means for holding said conveyor belts in spaced relation with each other, a pivotally mounted arm adapted to force a book between said conveyor belts, a drilling mechanism having a plurality of drill bits mounted therein, and a sewing head mounted upon said frame and underneath which the books are carried by the said conveyor belts.

Signed at Chicago, Illinois, this 24th day of July, 1923.
